UNITED STATES PATENT OFFICE.

WILLIAM M. BAILEY AND JOHN L. PULTZ, OF BOSTON, MASSACHUSETTS.

HANGER.

Application filed December 10, 1920. Serial No. 429,773.

The present invention relates to hangers, and is more particularly useful in supporting temporarily joists, plinths, floors and the like in building construction.

5 During the hardening or setting of the freshly poured concrete of concrete flooring, it is necessary to support temporarily portions of the floor, particularly the portions just above the supporting columns. According
10 to present practice, this support is obtained through wooden frameworks or plinths that are held in position under the flooring by temporary wooden scaffolding extending from floor to floor. Scaffolding
15 of this character is expensive to erect and to take down, because involving the use of highly paid, skilled labor, and is, furthermore, unsatisfactory because the heavy plinths are liable to fall when it is attempted to remove
20 the scaffolding, causing damage. The use of hangers has accordingly been suggested, but those of the types heretofore proposed have been so clumsy and awkward to manipulate that builders still prefer the unsatisfactory
25 and expensive scaffolding.

It is accordingly the object of the present invention to provide a new and improved hanger that shall be simple in construction, cheap, effective and easily applied and removed.

To this end, a feature of the invention resides in mounting a simply constructed hanger upon a convenient stationary supporting frame, the hanger being provided with a leg
35 that carries readily removable, adjustable supporting means for a joist or the like. By suitably adjusting or removing the supporting means, the joist, with the plinth or other framework supported thereon, may be
40 readily raised or lowered to any required degree, or removed altogether. The hanger is thus easily and readily manipulated, and the plinth, after the concrete has become sufficiently set, may be lowered away from
45 the flooring and held in lowered position until it is removed, element by element, by unskilled labor, and without danger of the mass falling as a whole upon the floor below and causing damage.

50 With the above end in view, the invention consists of the hanger hereinafter described, illustrated in the accompanying drawings, and defined in the appended claims.

The invention will be further explained
55 in connection with the accompanying drawings, in which Fig. 1 is a perspective view

of a flooring in process of construction, with parts broken away and omitted for clearness, showing a preferred form of hanger embodying the present invention; Fig. 2 is a 60 plan view of the same; Fig. 3 is a section taken upon the line 3—3 of Fig. 2, looking in the direction of the arrows; and Fig. 4 is a perspective view, on an enlarged scale, 65 of a portion of Fig. 1, showing more clearly the constructional details of the preferred hanger.

The hanger of the present invention may assume any of a number of different embodiments, one preferred form only being shown 70 in the drawings. It will be understood that the hanger may be employed in various arts to support many different types of structures. These structures may be typified in the joist or joists 2. A plinth, consisting 75 preferably of two plinth parts 4 and 6, separable at 8, may be supported upon and by a plurality of joists 2. The plinth shown for illustrative purposes is of the drop-panel form, as will be clear from Fig. 1, it being 80 understood that concrete will be poured therein and into the column shell 9 and allowed to harden or set. The hanger must be secured to some supporting framework, shown in the drawings as a beam 10 that 85 has already been previously fixed to the skeleton framework of the building in any well known manner.

In its broadest aspect, the preferred hanger of the present invention comprises a leg 90 12, supported by the beam or other supporting framework 10, and a supporting member 14, for supporting the joist 2 or other structure to be supported, and that is adjustable 95 along the leg 12 so as to be capable of supporting the joist 2 in any desired position along the member 12, and that is wholly removable from the leg 12. The leg 12 may extend in any desired direction from the supporting beam 10, but as it is desired, in 100 the present instance, to support the heavy, horizontally disposed plinth, it is shown extending downward. The supporting member 14 is provided with an opening 16 through which the leg 12 extends freely. A clamp 105 18, through an opening 20 of which the leg 12 extends, is provided with a clamping set screw 22 for clamping the clamp 18 to the leg 12, and thereby securing the supporting member 14, in any desired adjusted position.

To facilitate the mounting of the hanger

over the supporting beam 10, the leg 12 is preferably bent at 24 and 26 to form a U-shaped member. The bends 24 and 26 are made right angular, so that the U may fit snugly over the beam 10. A spacer or spreader 28 may be employed for the legs 12 and 30 of the U and may be provided with openings 32 and 34 through which the legs may extend. A clamp 36, similar to the clamp 18, may be mounted upon the leg 30 to maintain the spreader 28 tightly against the supporting beam 10. The supporting beam 10 is thus enclosed between the bend of the U and the spreader 28 and the hanger is tightly and rigidly clamped to the supporting beam. It is found, in practice, that the friction of the legs 12 and 30 against the walls of the openings 32 and 34 will usually be sufficient to maintain the spreader in position without the aid of the clamp 36. The clamp 36 may then be omitted, as is illustrated at the right in Fig. 1. It may be thought desirable, on the other hand, to employ a plurality of clamps 18 upon the leg 12, as is shown at the left in Fig. 1.

A plurality of hangers of the above-described character are usually secured to a supporting beam 10 at each of the four corners A, B, C and D of the plinth, their legs 12 extending through a plurality of openings 16 in a single supporting member 14. The hangers at the corners A and B may support the opposite ends of one or more joists 2. The hangers at the corners C and D may similarly support the opposite ends of other joists 2. The joists may, in turn, support the plinth, a plurality of joists 38 being preferably interposed. A very effective and easily manipulated support for the plinth is thus provided. The supporting members 14 may be pushed upward to force the joists 2 into tight engagement against the supporting beams 10 and there clamped tight by the clamps 18. When it is desired to remove the plinth, after the concrete has set, the clamps 18 may be lowered and re-secured at a lower elevation upon the legs 12. The joists 2 and the plinth supported thereby may then be easily removed, element for element. If desired, the clamps 18 may be removed altogether, and the plinth taken down as a unit.

The preferred hanger of the present invention may be cheaply constructed of iron rod or bar that is circular or square in cross section by simply bending the rod or bar at 24 and 26. The only additional apparatus required are the clamps 18 and 36, one for each hanger, the spreader 28, one for each hanger, and the supporting member 14, one for a plurality of the hangers. The spreaders 28 and the supporting members 14 may be of wood.

It will be clear that the invention is capable of considerable modification and change

by persons skilled in the art, and such modifications and changes are considered to be within the scope of the present invention, as defined in the appended claims.

What is claimed as new is:—

1. A hanger comprising a downwardly extending leg adapted to be secured to a support, means for clamping the leg to the support, a floor building structure being adapted to be tightly clamped to the support, means for holding the building structure tightly clamped to the support, the holding means being vertically adjustable upon the leg through a substantial range of vertical adjustment, and means for adjustably securing the holding means to the leg in a plurality of substantially different positions along the vertical to permit the building structure to be supported by the holding means in a plurality of substantially different positions along the vertical. 70

2. A hanger comprising a U-shaped member adapted to be mounted over a support, a spacer for the legs of the U, means carried by one of the legs of the U for clamping the spacer to the support, and supporting means carried by the other leg of the U. 80

3. A hanger comprising a U-shaped member adapted to be mounted over a support, means carried by one of the legs of the U for clamping the member to the support, and means carried by the other leg of the U for adjustably supporting a building structure. 85

4. A hanger comprising a plurality of U-shaped members adapted to be mounted over a supporting beam, a plurality of spacers, one for each U-shaped member, and each having openings through which the legs of the corresponding U-shaped member extend, so as to cause the beam to be enclosed between the bends of the U's and the spacers, and means carried by one leg of each U-shaped member for supporting a joist. 100

5. A hanger comprising a U-shaped member adapted to be mounted over a beam, a spacer having openings through which the legs of the U extend so as to cause the beam to be enclosed between the bend of the U and the spreader, means carried by one of the legs of the U for clamping the hanger to the beam, a joist-supporting member having an opening through which the other leg of the U extends, and means carried by said other leg for adjustably clamping the joist-supporting member and the joist to the beam. 110

6. A hanger comprising a plurality of U-shaped rods adapted to be mounted over a support, a spacer for each U-shaped rod, and a supporting member adjustably mounted on one leg of each of the U's for adjustably supporting a building structure. 125

7. A hanger comprising a plurality of U-shaped members adapted to be mounted over a support, means for securing the U-shaped 130

members to the support, and a supporting member secured to one leg of each or the U's having a plurality of openings through which the said legs extend.

- 5 8. The combination with a supporting beam and a joist that is adapted to be supported thereby, of a plurality of U-shaped members mounted over the beam, a plurality of spacers each having openings through
- 10 which the legs of one of the U-shaped members extend, so as to cause the beam to be enclosed between the bends of the U's and the spacers, means for adjustably clamping the corresponding U-shaped members and
- 15 the corresponding spacers to the beam, a joist-supporting member having openings through which extend one leg of each U-shaped member, and means carried by said last-named legs for adjustably clamping the joist-supporting member and the joist to the beam.

9. A hanger comprising a U-shaped member adapted to be mounted over a support, means for clamping the U-shaped member to the support, and means carried by one of the legs of the U for adjustably supporting a building structure through a substantial range of adjustment.

10. A hanger comprising a U-shaped member adapted to be mounted over a support, a spacer for the legs of the U, and adjustable supporting means carried by one of the legs of the U for adjustably supporting a building structure through a substantial range of adjustment.

11. A hanger comprising a plurality of U-shaped members adapted to be mounted over a support, means carried by one leg of each U-shaped member for supporting a building structure, and means for clamping the building-supporting means in position upon the said legs.

12. A hanger comprising a plurality of U-shaped members adapted to be mounted over a support with a leg of each U extending downwardly, a member carried by the said legs for supporting a floor building structure, the member having a substantial

range of adjustment upon the said legs along the vertical to adapt it to support the building structure in a plurality of substantially different positions along the vertical, means carried by the said legs for holding the member and the building structure tightly clamped to the support, the holding means being vertically adjustable upon the said legs through a substantial range of vertical adjustment, and means for adjustably securing the holding means to the said legs in a plurality of substantially different positions along the vertical to permit the member and the building structure to be supported by the holding means in a plurality of substantially different positions along the vertical.

13. A hanger comprising a plurality of U-shaped members adapted to be mounted over a support, a plurality of spacers, one for each U-shaped member, a member carried by one leg of each U-shaped member for supporting a building structure, means carried by the said legs for holding the member and the building structure tightly clamped to the support, the holding means being adjustable upon the said legs, and means for adjustably securing the holding means to the said legs in a plurality of different positions to permit the member and the building structure to be supported by the holding means in a plurality of different positions.

14. A device of the class described comprising a member having a leg and a portion bent away from the leg, a member adjustably mounted upon the leg, the said portion and the adjustably mounted member being adapted to engage a support between them, means for clamping the support between the said portion and the adjustably mounted member, and supporting means mounted upon the leg.

In testimony whereof, we have hereunto subscribed our names this 6th day of December, 1920.

JOHN L. PULTZ.
WILLIAM M. BAILEY.
